DESIGN FOR A CAP MEMBER FOR A DETACHABLE FASTENER OR THE LIKE

Sol Birnbaum, New York, N. Y.

Application April 24, 1940, Serial No. 91,906

Term of patent 3½ years

To all whom it may concern:

Be it known that I, Sol Birnbaum, a citizen of the United States of America, residing in New York city, in the Borough of Manhattan, county and State of New York, have invented a new, original, and ornamental Design for a Cap Member for a Detachable Fastener or the like, of which the following is a specification, reference being had to the accompanying drawing, forming part thereof, wherein,

I claim:

The ornamental design for a cap member for a detachable fastener or the like, substantially as shown.

SOL BIRNBAUM.
